[57] CLAIM

The ornamental design for the cabinet, as shown and described.

DESCRIPTION

FIG. 1 is a front elevational view of the cabinet comprising my new design;

FIG. 2 is a right side elevational view thereof, the opposite side elevational view being a mirror image thereof;

FIG. 3 is a top plan view thereof; and,

FIG. 4 is a front elevational view of an alternate embodiment of the cabinet comprising my new design, the sole difference between it and the first embodiment residing in the front elevation.

The broken lines shown in FIGS. 1 and 2 are for illustrative purposes only and form no part of the claimed design.
